UNITED STATES PATENT OFFICE.

SPENCER ALLEN STONE, OF CHILlicothe, Missouri.

PUMP.

1,171,273.

Specification of Letters Patent.

Patented Feb. 8, 1916.

Application filed June 5, 1914. Serial No. 843,196.

To all whom it may concern:

Be it known that I, SPENCER A. STONE, a citizen of the United States, and a resident of Chillicothe, in the county of Livingston

5 and State of Missouri, have invented certain new and useful Improvements in Pumps, of which the following is a specification.

My invention relates to pumps, and the main object thereof is to provide a plurality 10 of plungers in one cylinder in order to increase the pump capacity for given diameters.

A further object is to actuate said plungers independently, and in opposite directions at different times, by any suitable means; a further object is to telescope the stems for the said plungers, one within another, but in such manner as to be independently operable.

20 A further object is to provide suitable valves for the plungers which open freely on the downward plunger movement, but which close on the upward movement thereof.

25 A further object is to provide such a pump which dispenses with check valves.

A further object is to provide a pump with reciprocating plungers, which delivers a steady flow of water in the manner of a 30 centrifugal pump; and further objects are to provide such pumps which are simple in construction, assembling, installation and use, which are several times as efficient as pumps as heretofore constructed of the same 35 dimensions, and which are comparatively inexpensive.

My invention is fully described in the following specification, of which the accompanying drawings form a part, in which 40 the separate parts are designated by the same reference characters in each of the views, and in which:—

Figure 1 is a view of a pump constructed in accordance with my present invention, 45 the cylinder being in section, and one form of plunger operating means being shown; Fig. 2 is an enlarged, fragmentary, sectional, view of the cylinder and plungers, and showing the method of operating three 50 plungers; and Fig. 3 is a view of a detail of the operating means.

In the drawings forming a part of this application I have shown a cylinder 5, having a cap 6 at the upper end thereof provided with three packing boxes 7, 8, and 9, 55 and an outlet pipe 10 which may be pro-

vided with any suitable control means, a valve being shown at 11, and at the bottom of the cylinder is a union 12 to join other pipes or cylinders thereto.

Passing through the packing-box 7 is a rod 13 connected, detachably, with a plug 14 threaded into an elbow 15 in turn connected with a section of tubing 16 in turn mounted on a sleeve 17 which also has a 60 disk 18 and a tubular section 19 thereon, and being shouldered as shown at 20 to form a seat for a plunger head 21 having suitable perforations or ports therethrough, the tubular section holding said head in 65 place, and the tubular section 16, being threaded on the sleeve 17, holding the disk 18 and tubular section 19 in place, and slidably mounted on the tubular section 16 is disk-valve 22 normally forced against the 70 upper surface of the plunger head 21 by means of a spring 23 of sufficient strength to prevent the said valve from sticking, and maintain the same over the ports of the 75 plunger head under normal conditions.

Threaded into the plunger head is a bell 24 which fits the cylinder interior closely and around which is a collar 25, flexible washers 26 and 27 being held on said bell by the flange thereon and by said collar, as 80 clearly shown in Fig. 2, the ends of said bell being open to permit the free flow of water therethrough.

Slidably arranged in the sleeve 17 is a tubular stem 28 which carries a T-connection 90 adjacent its upper end, shown at 29, and to which is connected an elbow 30 having a plug 31 threaded thereto and into which is threaded a rod 32 slidable in the packing-box 8, and said tubular stem 28 is 95 connected at its lower end with a union 33 connected with another length 34 of the tubular stem and which is flanged at its bottom to form a shoulder serving as a support for a plunger head 35, a short tubular section 36 holding said head in place, whereas the union 33 holds the section 36 in place, as well as a disk 37, and I provide a disk-valve 38 for the head 35 and normally held 100 against the upper surface thereof by means of a spring 39, said valve being slidable on the section 36.

A bell 40 is threaded into the plunger head 35 and a collar 41 and washers 42 and 43 mounted thereon in the manner already 110 described with reference to the plunger head 21, and said head 35 is also provided

with suitable ports, and it will be seen from the foregoing that the plungers already described may be independently operated.

Slidable in the tubular stem 28 is a rod 44 which passes through the packing-box 9, and at its lower end is reduced in diameter and screw-threaded to engage a nut 45, serving to hold a plunger head 46 and sleeve 47 in place, a disk-valve 48 being slidable on said sleeve and normally forced against the ports in the head 46 by means of a spring 49, and I also employ a bell 50, washers 51 and 52, and collar 53 in the manner described with reference to the two other plunger heads 21 and 35, and at the lower end of the cylinder 5, in which said plungers operate, is a sand valve 54, of any desired form, and I also provide a disk 55 on the reduced portion of the rod 44 against which the spring 49 bears.

The plunger stem rods 13, 32, and 44 are in pivotal connection with links 56, 57, and 58, respectively, and which are in turn pivoted to corresponding parallel lever frames 59, 60, and 61, connected with a pivot 62 common to all and carried by a suitable support 63, said frames being oscillated by means of eccentric disks 64, 65, and 66 on a shaft 67 common to all, and arranged thereon at an angle of 120 degrees from each other, in the form shown, said shaft being rotated by means of a spur-gear 68 thereon, a pinion 69 on a power shaft 70, a pulley 71 thereon, and a belt 72, or in other desired manner.

It will be seen by this arrangement that the plunger rods 13, 32, and 44 are reciprocated in the cylinder 5, but in directions and at periods independent of each other, 40 governed by the cam arrangement, whereby there is one plunger moving up at all times, one moving down, and one alternating between the same, in this manner having two plungers approaching each other so that 45 the fluid being carried upwardly by one is forced into the space above the downwardly moving plunger, and giving a double quantity of fluid for each plunger operation, resulting in a correspondingly increased 50 delivery and, also, because of this plunger movement, delivering a constant flow through the discharge pipe 10.

The lower plunger in its downward movement passes through fluid raised by the 55 vacuum produced by one or the other of the plungers thereover in its upward movement, and, when the lower plunger rises, a quantity of fluid is raised thereby and which passes through the intermediate plunger 60 which is beginning to descend and, when the intermediate plunger rises, the upper plunger is beginning its descent and receives the fluid therefrom, whence it is carried to the discharge pipe, and this operation continues with the above results. The main

feature which makes this operation possible is the telescoped arrangement of the plunger stems permitting independent plunger operation, although I broadly claim the feature of the independently operable plurality of 70 plungers, irrespective of their number or arrangement, whereby I secure the advantages of a rapidly operated centrifugal pump in a slowly operating reciprocating plunger pump, and my pump, in smaller 75 sizes, may be manually operated, thereby adapting the same for use on farms, in factories, homes, and other places, and my pump is relatively easy in operation as the plunger movements are balanced to a cer- 80 tain degree.

My plungers and operating stems may be arranged in any suitable pipe, or combination of pipe lengths, and the plunger stems may be actuated in any desired manner, as I do not limit myself to the specific manner shown, nor indeed to any other manner, neither do I limit myself to the exact detail construction of the individual plungers, as many forms thereof would be 90 possible in design and, while I do specifically claim the telescoped arrangement of plunger stems as the simplest, most practical, and most economical, method, still other methods may suggest themselves and 95 still be within the scope of the following claims and, reserving the right to all changes in and modifications of the form shown and described,

What I claim as new and desire to secure 100 by Letters Patent, is:—

1. A pump comprising a cylinder, a plurality of plungers, a rod connected with one of said plungers, a hollow stem telescoping on the said rod, a shoulder formed on the 105 hollow stem, a plunger having its head supported on said shoulder, means for holding said head in place on the shoulder, a pipe connection secured on the upper end of said hollow stem, a rod connected with the said 110 pipe connection and means connected with the rods for actuating said plungers.

2. A pump comprising a cylinder, a plurality of plungers in said cylinder, a rod connected with one of the plungers, tubular 115 stems telescoping on each other, and on the said rod, the tubular stems being shouldered forming seats for the heads of the plungers carried by said stems, a tubular section on each tubular stem for holding the plunger 120 head in place on said shoulder, a tubular section on the upper end of each tubular stem, upwardly extending rods secured to said tubular sections, and means connected with the said rods for actuating the several 125 plungers.

3. A pump comprising a cylinder, a plurality of plungers in said cylinder, a rod connected with one of said plungers and extending upward beyond the top of the 130

nding upward above
, and means connected
r actuating the plun- 15
each other.
